ELECTRIC CIRCUIT BREAKER

Roland Dupont, Epernay, France

Application March 27, 1947, Serial No. 737,467
In France April 11, 1946

7 Claims. (Cl. 200—142)

1

The present invention relates to novel improvements in thermal circuit-breakers for use in electrically heated apparatus and adapted to cut out the current upon reaching a predetermined temperature.

The present invention is used preferably in connection with vulcanizing apparatus but may also be utilised for various other purposes such for instance as in a fire-alarm device.

An object of the present invention is a thermal circuit-breaker of the type wherein the electrical connection is ensured by means of a fuse pin or rod completely independent of the electric circuit, the rupture of which pin or rod causes the cut-out mechanism to operate, upon reaching a predetermined temperature.

Another object of my invention is to provide a thermal circuit-breaker with two different resiliently constrained systems, one of these being very weak and acting upon the fuse, while the other is much more powerful and acts upon the contact studs.

This arrangement has several distinct advantages:

First, the pressure exerted upon the fuse being very weak, the same is not subjected to any external force which would cause it to strain or to be ruptured prematurely. However, the spring force will be quite sufficient to rupture the fuse when the same upon being heated to the desired point has lost its mechanical resistance on account of molecular disintegration.

Secondly, the strain upon the contact studs being strong, the electrical connection is always at its best; moreover, the disconnection being brought into effect by the sliding movement of the movable contact studs upon the fixed studs, the frictional force exerted therethrough will result in keeping the contact members in the cleanest condition.

Besides, the movable contact studs are slidable upwardly which will cause the arc of rupture to initiate only on an extreme point at either the lower or upper end of the studs.

Thus, there is never any dirt or particles of metal left in the center of the contact studs, thereby always ensuring the best possible connection.

The objects and novel features of this invention will more fully appear from the following detailed description wherein like reference characters refer to like parts in the several views.

In the drawings:

Figure 1 is a vertical sectional view of my

2

thermal-circuit-breaker showing the same as attached to a vulcanizing apparatus.

Figure 2 is a similar section to Figure 1, but showing the first stage of the connecting operation.

Figure 3 is a cross sectional view with the top broken away taken on line 3—3 of Figure 4 which shows the device in operating position.

Figure 4 is a plane view of the device in operating position, the lid being taken off, and

Figure 5 is a partial view of a modification.

According to my invention, herein illustrated by way of example as attached to the heating members of a vulcanizing apparatus, the thermal circuit-breaker is arranged between two sides 1 and 2 integral with the cover 3 of the vulcanizing apparatus 4. The whole unit is kept under a lid 5.

The cover is provided with two fixed contact studs 6 and 7, and also with two ejecting lugs 8 and 9, a metallic heat-conducting hook 10 extending inside the device.

Two superposed transverse axles 11 and 12 are provided between the sides 1 and 2. Pivotally mounted upon the axle 11 is a movable operating member 13, the free end thereof being arranged as a table to receive the fuse 15. The member 13 forks into two branches 16 and 17, each provided with a flange 18 in its upper part, and with a flange 19 in its lower part. Both flanges 18 and 19 are positioned at right angles with member 13 in a direction towards the center thereof.

The operative member 13 is urged upwardly by means of a double tension spring 20 bearing upon the cover 3 and also upon the flange 18.

Also pivotally mounted upon the axle 11 by means of its branches 21 and 22 is a support 23 wherein a movable stud carrier is slidably engaged; the free ends of branches 21 and 22 opposite the axle are provided with flanges 24 positioned thereupon at right angle and directed towards the inside, so as to form a channel wherein the movable stud carrier is capable of sliding. Besides, the branches 21 and 22 have projections

25 and 26 extending laterally at right angle to a point adjacent to branches 16 and 17 of the operating member 13 in such a manner that said projections will be in the way of flanges 18 and 19. The movable stud carrier comprises two plates 27 and 28 held together transversely by an insulating member 29 and a bar 30, both acting as cross-pieces.

The ends of plates 27 and 28 opposite to the insulating member 29 are connected by a transverse bar 31 which extends outwardly on both

sides through openings 32 provided in both branches 21 and 22 of the support 23.

A tension spring 33 connects each end of the bar 31 with the right angle lateral extensions 25 and 26 of the branches 21 and 22.

A lever 34 pivoted at its center in a bearing 35 of the insulating member 29 is provided at its ends with contact studs 36 and 37 which are spaced apart in a like manner as the fixed contact studs 6 and 7.

The axle 12 has one end projecting outwardly from the side 2 and this extension forms an operating lever 38 fitted with a hand knob 39.

A stirrup-like member 40 is splined, or secured by any suitable means, upon the axle 12 and when the device is not in working position, said stirrup member bears, through gravity, against the flanges 18 of the operative member 13. The stirrup 40 is fitted centrally with a downwardly projecting leg 41 extending in the way of the cross-piece bar 30.

The device, being at rest, will be operated as follows:

A suitably shaped and calibrated fuse 15 is engaged through the slot 42 of the lid 5. Said fuse falls upon the table 14, in a temporary position, between an angle-shaped punched portion 43 and a practically V-shaped receiving member 44, having a central aperture.

The knob 39 is pressed, and thereupon, the stirrup 40 presses the flanges 18 of the operative member 13 which is thereby pivotally lowered. Simultaneously, the leg extension 41 of the stirrup 40 urges away the cross-piece bar 30 thus moving the movable stud carrier in a direction towards the axle 11, thereby releasing the contact studs which come into a position opposite the fixed studs 6 and 7, but without engaging the latter.

Upon reaching this position, the ejecting lugs 8 and 9 throw away the fuse 15 from its temporary position and the said fuse comes to rest within the V-shaped receiving member 44 under the nose of the hook 10 (Figure 2).

Upon release of the hand knob 39, two operations are effected simultaneously:

1. The tension springs 33 tend to urge back the stud carrier 30 to its previous position and the contact studs 36 and 37 engage the similar contact members 6 and 7; the cross-piece bar 30 urges the leg extension 41 away, and the stirrup 40 is released and urged upwardly;

2. The operative member 13, being released by the stirrup 40 starts a pivoting movement which is however limited by the fuse 15 now held fast between the V-shaped receiving member 44 and the nose of the hook 10 (Figure 3).

It is to be noted that the slight final upwardly directed movement of the operative member 13 does not affect the support 23, and therefore the contact studs 36 and 37, as the lower flanges 19 of member 13 are downwardly set-off so as to provide for a suitable space between the latter and the lateral extensions 25 and 26 of the support 23.

Upon reaching the selected temperature which was predetermined by the composition of the mixed metal constituting the fuse 15, the said fuse will start to disintegrate; the operative member 13 will then initiate an upwardly directed motion due to the softening of the fuse 15, but this movement does not affect the engagement of the contact members as previously explained. On the other hand, upon rupture of the fuse, the operating member is moved sharply upwards, and the flanges 19 thereof engage the branches 25 and

26 of the support 23 which is thus also urged upwards, thereby disengaging the contact members 36—37 from contacts 6—7 respectively.

As shown in the modification illustrated in Figure 5, the hook 10 may be replaced by a bimetallic strip 47; when in operating position, the end of the operative member 13 is engaged under the nose of the bimetallic strip, and upon reaching the predetermined temperature rated in relation with said bimetallic strip, the deflection of the latter will release the member 13. Said member will then move quickly upwards and the disconnection will thereby take place as previously explained.

Although only two embodiments of the invention have been illustrated and described, it will be readily understood that various changes in the form and relative arrangement of the parts to suit requirements may be made without exceeding the scope of the invention or departing from its spirit. It will also be apparent that the invention is not limited for use with a vulcanizing apparatus, and, for instance, may be utilised in connection with a fire-alarm or any other device wherein it is suitable to open or close an electric circuit upon reaching a predetermined selected temperature.

The object of my invention as herein described may also be used as a mere electric cut-out system. In this case, the hook 10 and the fuse 15 are to be replaced by any proper hand-operated mechanism whereby the operating member 13 may be actuated and thus the circuit broken.

I claim:

1. A thermal actuated circuit breaker for use with electrically heated apparatus comprising a fixed support, an electrical contact member fixedly mounted upon said support, an operating member pivotally connected to said support, resilient means interposed between said support and said operating member tending to pivot said operating member relative to said support, a pivotal support, an electrical contact carrier slidably carried by said pivotal support for movement longitudinally thereof, electrical contacts mounted on said carrier for engaging said first mentioned fixed contact member, temperature responsive means independent of the electrical circuit and capable of retaining said operating member against the action of said resilient means until a preselected temperature is reached, and means, carried by said contact carrier, for moving said movable contacts out of engagement upon release of said operating member by said temperature responsive means.

2. A thermal actuated circuit breaker for use with electrically heated apparatus as claimed in claim 1 in which spring means is interposed between said pivotal support and said slidable contact carrier for urging said contact into engagement with said fixed contact member when said operating member is in its closed circuit position.

3. A thermal actuated circuit breaker for use with electrically heated apparatus as claimed in claim 1 in which said resilient means tends to move said operating member in a direction which will cause the slidable disengagement of said fixed contact member from said movable contact for preventing an arc from forming between said contacts.

4. A thermal actuated circuit breaker for use with electrically heated apparatus as claimed in claim 1 comprising a manual controlled actuated member pivotally mounted on said support and

capable of urging said operating member into coupling position with said temperature responsive member, a leg extension carried by said actuating member for urging at the same time said ¹⁰ ₁₅ ₂₀ ₂₅ ₃₀
